INVENTOR:

Hermann Meyer

UNITED STATES PATENT OFFICE.

HERMANN MEYER, OF BERLIN, GERMANY, ASSIGNOR TO AUGUST RIEDINGER,
BALLONFABRIK AUGSBURG, AKTIENGESELLSCHAFT, OF AUGSBURG, GERMANY,
A GERMAN CORPORATION.

COLLAPSIBLE BOAT.

1,119,464.

Specification of Letters Patent. Patented June 13, 1922.

Application filed June 4, 1920. Serial No. 386,582.

To all whom it may concern:

Be it known that I, HERMANN MEYER, a citizen of the German Empire, residing at Berlin, Germany, have invented certain new and useful Improvements in Collapsible Boats, of which the following is a specification.

My invention relates to a collapsible boat and more especially to a boat provided with an annular tube which, if filled with air will keep the boat afloat, whereas after the air has been allowed to escape the tube and the parts connected therewith can be folded.

Boats of the type aforesaid, although offering a fair security against capsizing, becoming leaky and so on, involve owing to their unfavorable form the drawback of moving in the water only very clumsily and with great difficulty.

In the boat according to the present invention this drawback is obviated by employing a tube of peculiar form inasmuch as the diameter of the tube decreases towards the bow and stern both in horizontal and in vertical direction so that while the substantially straight lateral portions of the tube have a uniform large diameter, the narrower fore and aft portions have a diameter gradually decreasing towards the bow and stern respectively, and at the same time gradually rise above the water level. In this way a more favorable form of stream lines, as the boat is moving on, and, owing to the gliding effect of the ascending bow and stern portions, a diminution of friction between the boat hull and the water is obtained.

In the drawings affixed to this specification and forming part thereof the preferred form of a collapsible boat according to the present invention is illustrated. In the drawings—

Fig. 1 is a side elevation,

Fig. 2 a plan,

Fig. 3 a vertical longitudinal section on the line A—B in Fig. 2.

Fig. 4 a sectional view of the bow (or stern) portion, drawn to a larger scale.

Referring to the drawings, 1 is the annular tube keeping the boat afloat. As clearly shown in the drawing, its straight lateral portions have a larger diameter than the converging bow and stern portions 4 and 5, the diameter being smallest at 3. Besides thus reducing the diameter towards the ends

the lower faces 6 and 7, respectively, of the bow and stern portions 4 and 5 gradually ascend in vertical direction from the middle of the boat towards the bow and stern respectively.

10 is an air valve serving for introducing and expelling the air. 9, 9 are wooden boards surrounded by the tube and forming the boat's bottom, and 11, 11 are waterproof joints consisting for instance of some suitable fabric and connecting the single boards. 65 The bottom as a whole is connected to the canvas-cover (not shown) enclosing the tube by sewing or otherwise.

In order to impart to the boat the stability required for steering special collapsible 70 fin keels 12 are arranged at the bow and stern. 13, 13 are vertical rods or ledges linked to the boards 9 and connected with said keels, and 8, 8 are ropes, preferably wire-ropes, having one end fastened to the 75 bow and stern-portion, respectively, of the tube, while the other end is fastened to one of the boards 9 in the middle of the boat. As the tube is filled with air and expands, the keels 13 are stretched. On the other hand, 80 as the air is allowed to escape from the tube, the tension of the ropes 8, 8 diminishes and the keels are then folded automatically together with the boat itself. On the boat's bottom formed by the boards 9 seats, back- 85 rests 14 or the like may be arranged in any suitable manner.

I claim:—

1. A collapsible boat comprising an annular air-tube whose cross-section gradually decreases towards bow and stern.

2. A collapsible boat comprising an annular air-tube whose cross-section gradually decreases towards bow and stern, the lower faces of the bow and stern portions of 95 said tube extending in planes gradually ascending from the middle of the boat towards the ends.

3. A collapsible boat comprising an annular air-tube whose cross-section gradually decreases towards bow and stern, the 100 bow and stern portions of said tube converging towards the bow and stern.

4. A collapsible boat comprising an annular air-tube whose cross-section gradually 105 decreases towards bow and stern, the lower faces of the bow and stern portions of said tube converging towards bow and stern and

extending in planes gradually ascending from the middle of the boat towards the ends.

5. A collapsible boat comprising an annular air-tube whose cross-section gradually decreases towards bow and stern and boards linked to each other and connected with said tube so as to form the boat's bottom.

6. A collapsible boat comprising an annular air-tube whose cross-section gradually decreases towards bow and stern, boards connected with said tube so as to form the boat's bottom and watertight pliable connections between said boards.

15 7. A collapsible boat comprising an annular air-tube whose cross-section gradually decreases towards bow and stern, boards

linked to each other and connected with said tube so as to form the boat's bottom and collapsible keels fastened to the said bottom.

20

8. A collapsible boat comprising an annular air-tube whose cross-section gradually decreases towards bow and stern, boards linked to each other and connected with said tube so as to form the boat's bottom, stay ledges linked to said boards at the bow and stern, pliable skins connected with said ledges and ropes fastened to the free ends of said ledges and having their ends fixed to said tube and to the middle of said bottom 25 30 respectively.

In testimony whereof I affix my signature.

HERMANN MEYER.
